VISIBLE RECORD DEVICE AND DIVIDER
THEREFOR

Marchand B. Hall, Chicago, Ill., assignor to Acme
Visible Records, Inc., Chicago, Ill., a corpora-
tion of Delaware

Application April 22, 1946, Serial No. 663,865

7 Claims. (Cl. 129—16)

1

This invention relates to improvements in visible record card equipment, and refers specifically to a record card device of the type which carries dividers for indexing or otherwise separating the cards; and to a conveniently removable divider for use with such a device.

In visible record card systems wherein the cards are indexed or otherwise separated by removable dividers, it is desirable that the dividers be detachably secured to the base upon which the cards are supported, the attachment being such that the dividers can be easily removed or inserted at will.

An object of my invention resides in the provision of a divider construction wherein a suitable degree of attachment to the base is obtained and yet the divider can be quickly and conveniently removed when desired.

One of the specific advantages of my invention is that the removal or insertion of the divider is accomplished by a simple movement similar to that performed in removing or inserting the usual card, it only being necessary to exert a slightly greater degree of force than is necessary in the casual removal or insertion of one of the cards.

Another object of my invention resides in a divider construction wherein stresses encountered by attachment or detachment of the divider from the base are borne principally by a reinforcing frame comprising a portion of the divider, whereby such forces do not strain, tear, or tend to buckle the divider.

Other objects and advantages of my invention will be apparent from the accompanying drawing and following detailed description.

In the drawing,

Fig. 1 is a front elevational view illustrating my divider construction.

Fig. 2 is a fragmentary transverse sectional view taken on line 2—2 of Fig. 1.

Fig. 3 is an enlarged, detailed, sectional view taken on line 3—3 of Fig. 2.

Referring in detail to the drawing, 1 indicates a base upon which a record card system (not shown) is adapted to be supported. The base 1 may comprise a portion of a drawer or filing cabinet such as that shown and described in the co-pending application of Marchand B. Hall and Sylvan K. Ketterman, Serial No. 551,491, filed August 28, 1944, now Patent No. 2,435,077, dated January 27, 1948, upon a record filing device. The type of visible record equipment in which my present invention is to be used is similar to that described in the above identified co-pending application.

2

A supporting panel 2 is mounted upon base 1 intermediate the width of said base, said panel 2 traversing substantially the entire length of the base 1. The panel 2 comprises an upper face 3 which is provided with a plurality of spaced longitudinal beads 4. In the use of my device the beads 4 are adapted to support a plurality of record cards which are positioned in face to face relationship, the lower edges of said cards being in contact with the beads 4.

The upper portion 3 of the panel 2 is spaced from the upper face of the base 1 by means of flanges 5 which may be formed integral with the upper portion 3 of said panel. A ledge 6 joins the upper edge of each flange with the lateral edges of the member 3 whereby recesses 7 are provided by the said ledges and the base 1. It can readily be seen that the ledges extend through the length of the panel 2 and, hence, elongated recesses 7 are provided at the lateral sides of the panel 2.

As is usual with a record system of this type, the cards comprising the record are indexed or segregated into groups in any suitable manner by means of dividers. As has been hereinbefore described, the cards comprising the record are loosely positioned in face to face relationship with their lower edges supported by the beads 4. However, with devices of this kind it is desirable that the dividers or indexing elements be secured in some fashion to the base of the device. Preferably the manner of securing is such that the dividers can be quickly and conveniently removed at will.

One of the features of my present invention resides in the provision of a divider 8 which comprises a main panel portion 9 which may be constructed of cardboard, plastic or other relatively light thin material. The panel 9 is reinforced by a metal strip or frame 10 which embraces at least three edges of the panel as indicated in Fig. 1.

A lug 11 is secured at two adjacent corners of the panel 9 and comprises plates 12 and 13 which are adapted to embrace opposite faces of the panel 9. The lug 11 is secured to both the panel 9 and to the frame 10 by means of rivets 14 and 15 respectively.

Each lug 11 terminates at its lower end, which projects from the lower edge of the panel 9, in a circular sectioned sleeve 16. A cylindrical housing 17 is positioned in said sleeve, said housing comprising a cup-shaped member whose edges are crimped outwardly as shown best at 18 in Fig. 5 to provide an abutment against the mouth of

the sleeve 16. A cylindrical shell 19 is telescopically positioned within the cup-shaped member 17 and terminates in a bullet-shaped projection 20. A compression spring 21 is confined between the base of the cup-shaped member 17 and the shell 19, said spring urging the projecting head outwardly. The crimped edge of the cup-shaped member 17 is folded inwardly to provide an annular flange 22 which limits the outward movement of the shell 19.

In operation the dividers 8 are adapted to be detachably mounted upon the base 1. The distance between the adjacent edges of the opposite lugs 11 is slightly greater than the distance between the edges of the opposite ledges 6 whereby the projecting portions 18 and 22 of the cup-shaped members 17 can pass vertically downwardly over each side of the edges of the ledges 6. The distance, however, of the terminating ends of the bullet-shaped members 20 from each other are slightly less than the distance between opposite edges of the ledges 6. Consequently, when the panel 8 is mounted or removed from the base 1, the edges of the ledges 6 act upon the surfaces of the bullet-shaped members 20 to compress springs 21.

When the panel 8 is in its normal position upon the file, the bullet-shaped members 20 are positioned in the recesses 7 and, consequently, prevent casual or accidental removal of the divider 8 from the base. However, if sufficient vertical pull is exerted upon the panel 8, the bullet-shaped members 20 are caused to retract by contact of said members with the tapered surfaces of the ledges 6 whereby the divider 8 may be disengaged from the base. Likewise, by exerting a slight degree of force in moving the dividers 8 vertically downwardly, the bullet-shaped members 20 may be caused to be retracted in order to permit said members to pass over the edges of the ledges 6. To facilitate this operation the edges 23 of the ledges are rounded whereby vertical movement of the divider 8 produces a component force caused by the contact of the tapered surfaces of the bullet-shaped member and the rounded edges of the ledges to move the shell 19 inwardly against the springs 21.

Of course, it is to be understood that in so far as my present invention is concerned, the flanges 5 need not form an integral portion of the panel 2. However, in the preferred embodiment of my invention the panel 2 is preferably formed integral of the upper portion 3 and the flanges 5. It can readily be seen that when the divider 8 is so moved as to insert or detach the divider from the base 1, the stress caused by the compression of the springs 21 exerts a leverage upon lugs 11. This stress is essentially borne by the frame 10 which consequently permits the utilization of a relatively thin panel 9 without the sacrifice of rigidity of construction. In addition it can be seen that the removal or insertion of the divider 8 does not involve the canting or buckling of the divider, and comprises the comparatively simple motion of vertically moving the divider 8 upwardly or downwardly to disengage or engage the divider with the base.

By eliminating buckling of the divider or the necessity for the operator performing complicated gyrations with the divider in order to engage or disengage the same, considerable time is saved in removing or inserting my dividers, and the life of the dividers is materially increased by eliminating abuse by inexpert operators.

If desired, the dividers can be shifted longi-

tudinally of the base 1, that is, a divider may be removed and one or more dividers or cards may be shifted forwardly or backwardly, and the divider replaced in a new position.

5 I claim as my invention:

1. In a visible record card device, a supporting base, a flange extending at an angle to said base adjacent each lateral edge of said base and extending throughout substantially the length of said base, outwardly extending opposite ledges carried at the edges of said flanges spaced from said base to provide longitudinally extending recesses between said ledges and said base, a divider of greater width and length than thickness, and inwardly impelled resilient means carried at adjacent corners of said divider for positioning over said outwardly extending ledges and removable engagement in said recesses.
2. In a visible record card device, a supporting base, a flange extending at an angle to said base adjacent each lateral edge of said base and extending throughout substantially the length of said base, opposite ledges carried at the edges of said flanges and extending outwardly therefrom and being spaced from said base to provide longitudinally extending recesses between said ledges and said base, a divider of greater width and length than thickness, and inwardly impelled resilient means carried at adjacent corners of said divider for positioning over said outwardly extending ledges and removable engagement in said recesses, said resilient means being normally spaced a lesser distance than the distance between the edges of opposite ledges.
3. In a visible record card device, a supporting base, a flange extending at an angle to said base adjacent each lateral edge of said base and extending throughout substantially the length of said base, opposite ledges carried at the edges of said flanges and extending outwardly therefrom and being spaced from said base to provide longitudinally extending recesses between said ledges and said base, a divider of greater width and length than thickness, and engaging means carried at adjacent corners of said dividers for removable engagement in said recesses, said engaging means comprising arcuate surfaced members, and resilient means for urging each of said members inwardly toward said recesses.
4. In a visible record card device, a supporting base, a flange extending at an angle to said base adjacent each lateral edge of said base and extending throughout substantially the length of said base, opposite ledges carried at the edges of said flanges and extending outwardly therefrom and being spaced from said base to provide longitudinally extending recesses between said ledges and said base, said recesses opening oppositely to each other in an outwardly direction, a divider of greater width and length than thickness, and engaging means carried at adjacent corners of said dividers for removable engagement in said recesses, said engaging means comprising arcuate surfaced members, and resilient means for urging said members inwardly toward said recesses, said arcuate surfaced members being normally spaced a lesser distance from each other than the distance between the edges of said outwardly extending ledges, and being resiliently movable to a position to be simultaneously moved past the edges of said ledges.
5. In a visible record card device, a supporting base, a flange extending at an angle to said base adjacent each lateral edge of said base and extending throughout substantially the length of

said base, outwardly extending opposite ledges carried at the edges of said flanges remote from said base to provide outwardly facing longitudinally extending recesses between said ledges and said base, a divider of greater width and length than thickness, and engaging means carried at adjacent corners of said dividers for removable engagement in said recesses, said engaging means comprising lugs mounted upon said divider at adjacent corners of said divider, and spring pressed means carried by each of said lugs extending inwardly into opposite recesses and positionable over said ledges for engagement in said recesses.

6. A removable divider to be used with a visible record card device of the type having a base, a flange extending at an angle to said base adjacent each lateral edge of said base and extending throughout substantially the length of said base, and having oppositely extending ledges carried at the edges of said flanges remote from said base providing longitudinally extending recesses between said ledges and said base; comprising a substantially rectangular panel of greater width and length than thickness, means carried at adjacent corners of said panel for engagement in said recesses, said means comprising movable members and resilient means for urging said members toward each other and into said re-

15

cesses, and a metal frame reinforcing the sides of said divider not included between said means, said frame being joined to said means.

7. A removable divider for a visible record card system which comprises a reinforcing frame, a substantially rectangular panel of greater width and length than thickness carried by said frame, lugs mounted on adjacent corners of said frame, a tubular member carried by each lug and extending beyond an edge of said frame, an element slidably positioned in each tubular member, and springs positioned in said tubular member for urging said elements toward each other.
